UNITED STATES PATENT OFFICE

WILLIAM JAQUIERY, OF WATERBURY, CONNECTICUT, ASSIGNOR, BY MESNE ASSIGNMENTS, TO JOHNS-MANVILLE CORPORATION, OF NEW YORK, N. Y., A CORPORATION OF NEW YORK

MACHINE FOR PRODUCING STRIP MOLDINGS

Application filed July 1, 1929. Serial No. 375,015.

This invention relates to molding machinery, and more particularly to a machine for producing a continuous strip of folded molding from a strip of flat sheet metal.

One object of this invention is to provide a molding machine of the above nature in which an initially flat strip of sheet metal is drawn continuously through a series of dies and rolls, said strip being shaped into substantially tubular form around an interior mandrel, and subsequently flattened into final folded shape.

A further object is to provide a machine of the above nature which is adapted to be operated on a draw bench without the use of pulleys, belts, gears, or other similar mechanisms.

A further object is to provide a machine of the above nature in which the rolls and dies for forming up the metal strip are located in close proximity to one another, whereby the strip will be prevented from twisting out of position.

A further object is to provide a molding machine of the above nature in which all of the rolls and dies are mounted upon a single base so that it will be impossible for them to get out of alignment.

A further object is to provide a machine of the above nature in which a straight strip of folded molding may be continuously produced in one operation without requiring successive treatments in a plurality of machines as was the case in the previous practice.

A further object is to provide a machine of the above nature which will be simple in construction, inexpensive to manufacture, easy to manipulate, compact, and very efficient and durable in use.

With these and other objects in view there have been illustrated on the accompanying drawings three forms in which the invention may be conveniently embodied in practice.

Fig. 1 represents a top plan view of the assembled machine showing the flat metal strip entering at one end and the finished molding being drawn out at the other end.

Fig. 2 is a side sectional view of the same, the section being taken along the line 2-2 of

Fig. 1, looking in the direction of the arrows.

Fig. 3 is an enlarged sectional view, taken along the line 3-3 of Fig. 2, showing the preliminary or first forming die adapted to form the initially flat strip into the shape of a U.

Fig. 3a is a view showing the shape of the metal strip as it appears after passing through the first forming die illustrated in Fig. 3.

Fig. 4 is an enlarged sectional view showing the starting and squaring up rolls, said section being taken along the line 4-4 of Fig. 2.

Fig. 4a is a view showing the shape of the metal strip as it appears after passing through the starting and squaring up rolls illustrated in Fig. 4.

Fig. 5 is an enlarged sectional view, taken along the line 5-5 of Fig. 2, showing the mandrel, anvil and edge-bending block.

Fig. 5a is a view of the metal strip as it appears after passing the edge-bending block illustrated in Fig. 5.

Fig. 6 is an enlarged sectional view, taken along the line 6-6 of Fig. 2 showing the first forming rolls and the mandrel.

Fig. 7 is an enlarged sectional view, taken along the line 7-7 of Fig. 2 showing the second forming dies and the mandrel.

Fig. 8 is an enlarged sectional view, taken along the line 8-8 of Fig. 2 showing the top bending and base-flattening rolls.

Fig. 9 is an enlarged sectional view, taken along the line 9-9 of Fig. 2 showing the final finishing dies.

Fig. 10 is a perspective view, on a reduced scale, of the wall of a bathroom showing the use of three different forms of molding which may be produced by this machine.

Fig. 11 is a sectional view, taken along the line 11-11 of Fig. 10, showing the use of the ordinary or flat form of molding for covering the joint between two sheets of wall paneling located in the same plane.

Fig. 12 is a sectional view on an enlarged scale, taken along the line 12-12 of Fig. 10, showing the use of the convex form of molding which may also be produced by the machine, said molding being applied to an out-

side corner of the room for covering the joint between two perpendicular sheets of wall paneling.

Fig. 13 is a sectional view on an enlarged scale, taken along the line 13—13 of Fig. 10, showing the concave form of molding used on the inside corner of the room.

The present invention is an improvement on the invention disclosed in the prior Patent No. 1,461,848, granted July 17, 1923, to the same inventor.

Referring now to the drawings in which like reference numerals denote corresponding parts throughout the several views, the machine comprises a casing generally indicated by the numeral 10, said casing being adapted to be detachably mounted upon the bed plate of a draw bench, not shown, by a pair of flat front and rear brackets 11 and 12, as shown in Fig. 1. The brackets 11 and 12 have slots 13 and 14 in the ends thereof for receiving screws, not shown, for attaching the machine to said bed plate.

The casing 10 consists of a left-hand side frame 15 and a right-hand side frame 16, as viewed in Figs. 3 to 9, said frames 15 and 16 being braced by the flat brackets 11 and 12 previously mentioned. The side frames 15 and 16 are connected at their tops by a rectangular open strip 17, a rectangular closed strip 19, and a straight cross-strip 21, as clearly shown in Figs. 1 to 9. The strips 17, 19, and 21 are secured to said frames 15 and 16 in any suitable manner, preferably by screws, not shown, and said strips have suitable openings for permitting adjustment of the dies and rolls carried therewithin.

The side frames 15 and 16 are joined at their bottoms by cross-strips 22, 23, and 24, secured in place, as by screws, not shown.

Preliminary forming die

The first operation of the machine is to bend the initially-flat strip 25, shown at the left of Figs. 1 and 2, into the U-shape shown in Figs. 3 and 3a. This is accomplished by a preliminary or first forming die consisting of an upper ribbed member 26 and a lower grooved member 27 through which the strip 25 is drawn. The members 26 and 27 of the preliminary die are rigidly carried between the side frames 15 and 16 and are adjustable within the top and bottom strips 17 and 22.

Starting and squaring up rolls

In order to start the pointed tip of the molding strip through the machine into position to be clamped by the jaws of the draw bench tongs, not shown, provision is made of a pair of starting rolls 28 and 29, most clearly shown in Figs. 1, 2, and 4. These starting rolls which have convex and concave peripheries respectively, are mounted with the opening therebetween in alinement

with the opening in the preliminary forming die. The rolls 28 and 29 also serve to square up the sides of the U-shaped strip into exact parallelism.

The rolls 28 and 29 are rigidly carried on shafts 28a and 29a journaled within two pairs of opposed bearing blocks 30 and 31, and said shafts are adapted to be adjusted relative to each other by means of set screws 32 and 33 located respectively in the top of the strip 17 and in the side strips 34 and 35 connecting the bottom cross-strips 22 and 23. The shafts 28a and 29a are extended outwardly at one side of the machine for receiving a pair of intermeshing gears 36 and 37.

The upper shaft 28a also has a square end 37a for receiving a starting handle 38, the manual rotation of which causes said rolls 28 and 29 to turn in opposite directions and drive the strip forwardly through the machine.

Anvil and mandrel holder

In order to support the U-shaped strip as it leaves the starting and squaring-up rolls 28 and 29, provision is made of a grooved anvil 39 and a mandrel holder 40, the latter being rounded to fit within the interior of the groove in the anvil.

The anvil 39 is rigidly held in position by a pair of cross-bolts 41 and 42 mounted in the side frames 15 and 16, and the mandrel holder is rigidly held by a pair of posts 43 and 44 depending from the side frame 15.

Edge-bending block

After passing through the starting and squaring-up rolls 28 and 29, the edges of the U-shaped strip are next bent inwardly into a horizontal position, as shown in Figs. 5 and 5a by means of a V-shaped flat bending block 45. The block 45 is adjustably carried by a bracket 46 secured on the side frame 16 above the anvil 39 and mandrel holder 40, as by a set screw 47.

Mandrel

In order to form a support for the interior of the tubular strip until it is squeezed out into the final flat shape shown in Fig. 9, provision is made of a solid mandrel 48, the shape of which varies along its length in the manner to be hereinafter described. The mandrel 48 has a threaded rear end 49 screwed into a threaded hole formed in the mandrel holder 40. The other or front end 49a of the mandrel terminates just beyond and is supported in the final finishing die (Fig. 9) as will be hereinafter more fully described.

First forming rolls

After passing beyond the anvil 39 and the mandrel holder 40, the metal strip, now in substantially tubular form and with its in-turned edges located in close proximity to each other, will be formed up into substan-

tially oval shape by means of a pair of forming rolls 50 and 51.

The first forming rolls 50 and 51 are mounted to rotate on a pair of vertical studs 52 and 53 screwed into a pair of angle brackets 52a and 53a, the side frames 15 and 16 being cut down at this point, as shown in Figs. 2 and 6. The vertical arms 52b and 53b of said angle brackets carry horizontal adjusting screws 52c and 53c which are mounted in threaded holes in the side frames 15 and 16. The shapes of the rolls 50 and 51 and the interior mandrel 48 are so arranged that the oval shaped tubular strip at this point will be somewhat restricted at a point slightly above its centre, and above and below the restricted sections, will be somewhat enlarged.

Second forming die

20 Immediately adjacent the first forming rolls 50 and 51 and in alignment with the opening between them, provision is made of a second forming die consisting of a pair of complementary upper and lower members 54 and 55, rigidly housed within the side frames 15 and 16 and adjustable within the top and bottom strips 19 and 23. Within this die, the base of the tubular strip is considerably enlarged and widened, while the top thereof remains substantially of the same shape as in the first forming rolls 50 and 51.

Base flattening rolls

35 The tubular strip next passes through a pair of horizontal substantially cylindrical rolls 56 and 57 rigidly mounted on shafts 58 and 59 journaled in adjustable bearing blocks 60 and 61 respectively. The upper roll 56 has a smooth surface and is adapted to press the top edges of the strip down into a pair of grooves 62 and 63 formed in the mandrel 48 at this point. The bottom roll 57 has a flat recessed central portion 63a to cause the bottom of the tubular strip to assume a flat horizontal shape, as shown in Fig. 8. Set screws 64 and 65 similar to the set screws 32 and 33 are provided for adjusting the bearing blocks 60 and 61 within the side frames 15 and 16.

50 The lower portion of the mandrel 48 at this point is cut away preparatory to the flattening up of the base of the hollow molding strip in the next succeeding operation.

Final finishing die

55 The tubular strip which at this point is supported only at its upper portion by the mandrel is next passed through the final finishing die consisting of a pair of complementary upper and lower members 66 and 67 rigidly carried within the side frames 15 and 16 and adjustable within the top and bottom strips 21 and 24. Within this finishing die, the base 69 of the molding strip 68 is squeezed compactly together into the final flattened folded shape desired, with the sides 70 and 71

slightly upturned and the convex edges or locking beads 72 and 73 spaced apart as shown in Figs. 9 and 11.

If it is desired to produce molding strips having shapes different from the first form illustrated in Figs. 9 and 11, it will only be necessary to substitute for the finishing dies 66 and 67 other finishing dies as needed. Thus, for example, by suitably shaped finishing dies, not shown, the molding 74, shown in Fig. 12, may be produced, the top portion of said molding 74 being identical with that of the molding 68 but having a convex substantially semi-circular folded base.

Similarly, the form of molding 75, shown in Fig. 13, may also be produced by the use of the proper finishing die, not shown. In this form of molding the top is the same as the first two forms 68 and 74 but the base is made concave.

80 One important use of the molding strips formed by the present machine is for covering the joints between adjacent panels in a bathroom, lavatory, or other room. This use of the invention is illustrated in Figs. 10-13 where the numerals 76, 77, 78, and 79 indicate four adjacent panels of a bathroom.

85 In order to securely hold the molding strips in position covering the above-mentioned joints, provision is made of a plurality of U-shaped clamping jaws or grooved attaching members 80 which are laid in the grooves of said joints and are fastened in place as by nails 81. The molding strips 68, 74 or 75 will then be forced inwardly until the small jaws 72 and 73 have been driven between the side legs of the U-shaped attaching members 80. The resiliency of the metal of said side legs will thereafter serve to retain or lock the molding strips tightly in position.

90 As clearly shown in Figs. 10-13, the flat form of molding strip 68 will be used to cover the joint between two wall panels which are located in the same plane, the convex form 74 for covering the joint between perpendicular panels at an outside corner, and the concave form 75 for covering the inside joint between perpendicular panels at an inside corner.

95 While there have been disclosed in this specification three forms in which the invention may be embodied, it is to be understood that these forms are shown for the purpose of illustration only, and that the invention is not to be limited to the specific disclosures but may be modified and embodied in various other forms without departing from its spirit. In short the invention includes all the modifications and embodiments coming within the scope of the following claims.

100 Having thus fully described the invention, what is claimed as new, and for which it is desired to secure Letters Patent, is:

1. In a machine for producing a thin molding, means for bending a longitudinally

- moving strip of metal into U-shape, means for forming spaced locking beads on the edges of said strip, and means for folding the portion of said strip below said beads into a pair of aligned flat side sections.
2. In a machine for producing a thin molding, means for bending a longitudinally-moving strip of metal into U-shape, means for forming spaced locking beads on the edges of said strip, means for forming the lower portion of said U-shaped strip into substantially oval shape having a curved base and sides, means for flattening said base and sides, and means for folding said flattened base and sides into contact to form a pair of aligned side sections.
3. In a machine for producing a thin molding having an open top seam and a folded flat base, means for bending a longitudinally-moving metal strip into U-shape, a mandrel, means for shaping the lower portion of said U-shaped strip over said mandrel into substantially oval form, means for flattening the base and sides of said oval lower portion into substantially triangular shape while the interior of the strip is unsupported, and means for folding said flattened base and sides into contact.
4. In a machine for producing a thin molding having an open top seam and a folded flat base, means for bending a longitudinally-moving metal strip into U-shape, means for forming flanges on the upper edges of said strip, means for simultaneously bending said strip into a double oval shape having an open top, and means for squeezing the sides of the base of said oval strip into flat contact.
5. In a machine for continuously producing a folded molding, means for bending an initially flat moving strip of metal into partly tubular shape, means for forming inwardly bent spaced flanges on said partly tubular shaped strip, means for enlarging and flattening the base of said partly tubular shaped strip, and means for squeezing the sides of said enlarged base into flat contact to form a covering for the joint between two adjacent wall panels.
6. In a machine for producing a thin molding having an open top seam and a folded flat base, means for bending a longitudinally-moving metal strip into U-shape, a mandrel, means for shaping the lower portion of said U-shaped strip over said mandrel into substantially oval form, a roll for flattening the base and sides of said oval lower portion into substantially triangular shape while the interior of strip is unsupported, and means for folding said flattened base and sides into contact.
7. In a machine for producing a thin molding having an open top seam and a folded flat base, means for bending a longitudinally-moving metal strip into U-shape, a mandrel, means for shaping the lower portion of said
- U-shaped strip over said mandrel into substantially oval form, a pair of rolls cooperating with an extension of said mandrel for flattening the base and sides of said oval lower portion into substantially triangular shape while the interior of said strip is unsupported, and means for molding said flattened base and sides into contact.
8. In a machine for producing a folded molding from a strip of sheet metal, a die for bending said strip into U-shape, a pair of rolls for initially forcing said strip through said machine, a mandrel for supporting the inner surface of said strip, an angular plate for bending the edges of said strip inwardly, a pair of rolls for forming said U-shaped strip into substantially oval shape, a die for enlarging the base of said oval-shaped strip, a roll for flattening said base, and a die for squeezing the sides of said base together.
9. In a machine for producing a folded molding from a strip of sheet metal, a die for bending said strip into U-shape, a pair of power driven rolls for initially forcing said strip through said machine, a mandrel for supporting the inner surface of said strip, an angular plate for bending the edges of said strip inwardly, a pair of rolls for forming said U-shaped strip into substantially oval shape, a die for enlarging the base of said oval-shaped strip, a roll for flattening said base, and a die for squeezing the sides of said base together.
10. In a machine for producing a folded molding from a strip of sheet metal, a die for bending said strip into U-shape, a pair of gear driven rolls for initially forcing said strip through said machine, a mandrel for supporting the inner surface of said strip, and angular plate for bending the edges of said strip inwardly, a pair of rolls for forming said U-shaped strip into substantially oval shape, a die for enlarging the base of said oval-shaped strip, a roll for flattening said base, and a die for squeezing the sides of said base together.
11. In a machine for producing a folded molding from a strip of sheet metal, a die for bending said strip into U-shape, a pair of rolls for initially forcing said strip through said machine, a mandrel for supporting the inner surface of said strip, an anvil for supporting said mandrel, an angular plate for bending the edges of said strip inwardly, a pair of rolls for forming said U-shaped strip into substantially oval shape, a die for enlarging the base of said oval-shaped strip, a roll for flattening said base, and a die for squeezing the sides of said base together.
12. In a machine for producing a folded molding from a strip of sheet metal, a die for bending said strip into U-shape, a pair of rolls for initially forcing said strip through

- said machine, a mandrel for supporting the inner surface of said strip, a holder for said mandrel, an angular plate for bending the edges of said strip inwardly, a pair of rolls 5 for forming said U-shaped strip into substantially oval shape, a die for enlarging the base of said oval-shaped strip, a roll for flattening said base, and a die for squeezing the sides of said base together.
- 10 13. In a machine for continuously producing a folded molding, means for bending an initially flat moving strip of metal into U-shape, means for forming inwardly bent spaced flanges on said U-shaped strip, means 15 for enlarging and flattening the base of said U-shaped strip, and means for squeezing the sides of said enlarged base into flat contact to form a covering for the joint between two adjacent wall panels.
- 20 14. In a machine for continuously producing a folded molding, means for bending an initially flat moving strip of metal into U-shape, means for forming inwardly bent spaced flanges on said U-shaped strip, means 25 for enlarging and flattening the base of said U-shaped strip, and means for squeezing the sides of said enlarged base into contact to form a covering for the joint between two adjacent wall panels.
- 30 15. In a machine for continuously producing a folded molding, means for bending an initially flat moving strip of metal into U-shape, means for forming inwardly bent spaced flanges on said U-shaped strip, means 35 for bending said flanges to form a pair of opposed convex beads for detachable engagement within the grooved joint between two panels, means for enlarging and flattening the base of said U-shaped strip, and means 40 for squeezing the sides of said enlarged base into flat contact to form a covering for the joint between said adjacent wall panels.
- 45 16. In a machine for continuously producing a folded molding, means for enlarging and flattening the base of a U-shaped strip, and means for squeezing the sides of said enlarged base into flat contact to form a covering for the joint between two adjacent wall panels.
- 50 17. In a machine for producing a molding, means for continuously bending an initially-flat longitudinally-moving strip of sheet metal into U-shape, a mandrel for supporting the upper part of said U-shaped strip, and 55 means for forcing the lower unsupported portion of said strip outwardly into two flat folded side sections.
- 60 18. In a machine for producing a thin molding of double-thickness sheet metal having a pair of upstanding locking beads on one side to be detachably inserted within a plurality of clamping jaws located in the seam between a pair of panels, means for bending said strip into U-shape, means for flanging 65 the edges of said U-shaped strip, means to

form said flanged edges into locking beads, and means for enlarging, flattening and squeezing the lower portion of said U-shaped strip into a pair of aligned, opposed side sections with their inner surfaces in contact. 70

In testimony whereof, I have affixed my signature to this specification.

WILLIAM JAQUIERY.
